UNITED STATES PATENT OFFICE.

LYMAN H. DAY, OF NEW YORK, N. Y., ASSIGNOR TO THE BRADLEY, VOORHEES & DAY MANUFACTURING COMPANY, (LIMITED,) OF SAME PLACE.

METHOD OF FASTENING STIFFENING-STRIPS TO GARMENTS.

SPECIFICATION forming part of Letters Patent No. 366,936, dated July 19, 1887.

Application filed February 7, 1887. Serial No. 226,770. (No model.)

To all whom it may concern:

Be it known that I, LYMAN H. DAY, of the city, county, and State of New York, have invented a new and useful Improved Method 5 of Fastening Stiffening-Strips to Garments, of which the following is a full, clear, and exact description.

This invention, although applicable to garments of different kinds, is more particularly 10 designed to be used in connection with knitted elastic garments—such as those termed “jerseys”—worn by women and children. In such garments a lining is usually dispensed with as being objectionable for several reasons. 15 Thus a lining gives increased thickness to the garment, does not stretch or yield with the garment, and in stitching it to its place unsightly rows of stitching appear upon the outside of the garment. These objections and 20 the additional expense of lining more than counterbalance the main advantage which is derived from such lining—namely, of preventing the garment from riding up on the body of the person and getting out of form and place. 25 My invention accordingly relates to garments, especially garments made without a lining, composed of separate pieces of material united by one or more seams, the free turned-in marginal portions of which are stitched 30 together on the inside of the garment, and in which said seams have combined with or applied to them stiffening-strips arranged to run in direction of the length of the seams.

The invention embraces a novel method of 35 thus applying stiffening-strips to the seams of the garment, which consists in uniting each stiffening-strip to its respective garment-seam by inclosing the strip within or between the turned-in marginal portions of the seam and 40 uniting said turned-in portions to each other along the opposite or both longitudinal margins of the stiffening-strip. By this method the garment may not only be kept down and in place on the body without having resort to 45 a lining for the purpose, and without exposing on the exterior any more seams or lines of stitching than are necessary in the construction of the garment without a lining, but the turned-in marginal portions of the seams,

which are integral with the main material of 50 the garment, are made to form pockets for inclosing and holding the stiffening-strips in place, substantially as hereinafter described, and shown in the drawings.

Reference is to be had to the accompanying 55 drawings, forming part of this specification, in which similar letters of reference indicate corresponding parts in both the figures.

Figure 1 represents a view of a female figure, in part, fitted with a garment known as 60 a “jersey,” which is represented as partly broken away for the purpose of illustrating a stiffener or stiffening-strip and the mode of applying the same to one of the seams of the garment. Fig. 2 is a transverse sectional view, 65 upon a larger scale, of the seam of the garment with the stiffener applied to and inclosed by it.

A is the garment, made without a lining and composed of a series of sections or pieces united by seams b. Each or any or all of 70 these seams may have the inside stiffeners, which restrain the garment from riding up and serve to keep it in form and place on the body of the wearer applied to it or them; but it will suffice here to describe the stiffener as 75 applied to only one of the seams.

B is the stiffener or stiffening-strip, made of whalebone or any other suitable material, arranged to run throughout the length of the 80 seam or any part thereof.

The turned-in marginal flap-like portions d d of the seam are made of an increased width or depth to receive the stiffener B lengthwise between them and to provide for securing said stiffener within them by uniting the 85 turned-in marginal portions d d of the seam along the opposite or both longitudinal margins of the stiffener or stiffening-strip, as by inner and outer rows of inside stitching e f, the one, e, of which may be the usual stitching 90 for closing the seam. After the stiffener has thus been inclosed and secured within the turned-in marginal portions d d of the seam as a pocket, said stiffener, together with the portions d d of the seam, should be subsequently laid or pressed down flat upon the inside of the garment.

Having thus described my invention, what I

claim as new, and desire to secure by Letters Patent, is—

The method herein described of fastening stiffening-strips to the seamed portions of garments, which consists in uniting each stiffening-strip to its respective garment-seam by inclosing the strip within or between the turned-in marginal portions of the seam and uniting

said turned-in portions to each other along the opposite or both longitudinal margins of to the stiffening-strip, substantially as specified.

LYMAN H. DAY.
